BOAT PROPELLING DEVICE

Bogoa Strezzoff, Minneapolis, Minn.

Application August 20, 1936, Serial No. 96,992

1. Claim. (Cl. 115—24)

This invention relates to devices or mechanisms for propelling a small boat, such as a row boat, punt or canoe.

It is an object of my present invention to provide a small compact propelling unit for boats which may be quickly and easily installed and which is driven by a crank shaft operated by a pumping action from the feet or hands of the operator.

10 It is a further object to provide a propelling unit of the class described wherein provision is made in the unit and propeller-supporting means for turning and steering the boat.

More specifically it is an object to provide a compact boat propelling device wherein all working mechanism is mounted upon a suitable standard or mounting adapted to be readily secured to the bottom of the boat and wherein provision is made for conveniently supplying hand or foot power to produce a rapid revolution of the propeller and wherein, moreover, provision is made in the construction of the propeller mounting and its supporting sleeve to enable the boat to be effectively steered.

25 In my improved structure, the propeller driving shaft extends vertically and is housed in a sleeve which extends through the bottom of the boat and carries at its lower end a closed housing for the propeller. The said housing is mounted to constitute a rudder whereby the boat may be steered by oscillating its supporting sleeve.

These and other objects and advantages of the invention will be more fully set forth in the following description made in connection with the 35 accompanying drawing, in which like reference characters refer to similar parts throughout the several views, and in which:—

Fig. 1 is a view showing a flat bottomed boat which has installed therein an embodiment of 40 my propelling unit, said unit being shown in side elevation;

Fig. 2 is a vertical section taken approximately axially of the tubular mounting of the standard;

Fig. 3 is a front elevation of my propelling 45 mechanism; and

Fig. 4 is a top plan view of the same.

As shown in the drawing, my boat propelling unit is installed in a flat bottomed row boat B having the usual bottom 5 provided with a keel 6 and having the stern seat 7 supported, as shown, by cleats 8 secured to the side walls of the boat. My propelling unit is mounted forwardly of the rear seat in convenient position to be paddled by the occupant of the seat as well as steered from 55 the seat,

My improved mechanism, as shown, includes an upright tubular mounting 9 having a base flange 9a which is secured by bolts or other suitable means to the bottom of the boat, preferably above the keel 6. The tubular mounting is provided adjacent its upper and lower ends, respectively, with suitable bearings 10 and 11 in which is journaled for oscillation, an upright steering sleeve 12. Steering sleeve 12, as shown, carries a thrust flange 12a adjacent its upper end which is supported upon the upper end of the mounting 9 to retain the sleeve against longitudinal displacement. The lower end of sleeve 12, as shown, projects through the bottom of the boat and the keel 6 and a suitable packing gland 13 surrounds the depending portion of the sleeve forming a sealed joint between the sleeve and the bottom of the keel.

To the depending end of steering sleeve 12 is secured a housing 14 which is preferably tapered in a horizontal plane from its rear to its forward end, to furnish as little obstruction to the water as possible in the movement of the boat and this housing is of such length and surface area as to constitute an efficient rudder for the boat, its 25 operation being controlled by the oscillation of sleeve 12. A suitable stub propeller shaft 15 is journaled at its rearward and forward portions in housing 14 and the propeller 16 is affixed to the rear extremity of said stub shaft, as clearly 30 shown in Figs. 1 and 2.

A vertical propeller-driving shaft 17 is suitably journaled in upper and lower bearings carried by the steering sleeve 12 (see Fig. 2) and has a bevel gear 18 affixed to the lower end thereof 35 below the lower end of sleeve 12, which bevel gear is affixed to the stub shaft 15 within the housing 14. As shown, the bevel gear 18 is of greater diameter than the gear 19, causing revolution of the propeller at a somewhat greater speed than 40 the revolution of the propeller-driving shaft.

At the upper end of the propeller-driving shaft 17, a bevel gear 20 is secured, being meshed with a larger bevel gear 21, journaled for revolution on a horizontal axis and mounted in a rigid supporting bracket 22 secured to the upper portion of the tubular mounting 9. Bevel gear 21 is affixed to a stub shaft 21a which rigidly carries, at its outer end, a gear 23 meshed with a relatively large gear 24 which is affixed to a crank 50 shaft 25, suitably journaled in bearings affixed to the vertical mounting 9 and extending, as shown, rearwardly thereof. The crank shaft 25, is provided with a pair of crank arms 25a disposed 180 degrees apart and terminating in crank 55

pins to which foot pedals 26 are pivotally attached.

The crank shaft 25 is located at a suitable height to enable it to be conveniently paddled 5 by a person sitting on the rear seat of the boat.

To conveniently steer the boat from the seat 7, I provide a steering shaft 27 journaled in a rugged bracket 28 which is affixed to the rear 10 of the tubular mounting 9, the bearings for said shaft having a common axis and being inclined at a convenient angle to the vertical. The lower end of the shaft 27 is provided with a bevel gear 29 which is meshed with a larger bevel gear 30 rigidly fixed to the upper end of the steering 15 sleeve 12.

All of the moving parts, it will be noticed, are secured to or supported from the rugged mounting or standard 9 and are very compactly arranged with respect to each other and with said 20 mounting.

In operation, the operator sits upon a seat conveniently located behind the unit and pedals the crank shaft while holding on to the steering wheel, thus steadyng himself and facilitating the 25 pedalling of the crank shaft. The transmission means between the crank shaft and the propeller including the large gear 24, small gear 23, the bevel gears 20 and 21 and the bevel gears 18 and 19 disposed within the housing, cause the 30 propeller to be revolved at a relatively high speed compared with the speed of the crank shaft.

To steer the boat, it is only necessary to manipulate the steering wheel 27a which turns the steering sleeve 12 and the rudder housing 14 with 35 the propeller mounted therein.

The unit is very quickly attached to the boat by merely forming a suitable hole through the bottom and keel of the boat through which the rudder sleeve 12 may be projected. The upright

mounting 9 is then attached by its base 9a to the bottom of the boat and the housing 14 is then secured to and sealed with the lower end of sleeve 12 below the bottom of the boat.

In the operation of my device, the large gear 5 24 having considerable weight acts as a fly-wheel for the device shifting in the production of a steady propelling power.

From the foregoing description, it will be seen that I have provided a very simple and compact 10 boat propelling unit which is adapted to be manufactured at relatively low cost and which enables an operator to drive manually or by foot power a small boat at fair speed.

What is claimed is:—

In a boat propelling device, an upstanding mounting adapted to be secured to the bottom of a boat, a hollow casing rotatably mounted within said mounting and extending through the bottom of said boat, a propeller mounted for 20 rotary movement on a horizontal axis, and secured for movement with said hollow casing on a vertical axis, a vertical propeller driving shaft extending upwardly through said hollow casing and said mounting, a power gear mounted beside 25 the exterior of said mounting, a crank shaft for driving said power gear, said hollow casing extending upwardly through said mounting, said vertical drive shaft extending upwardly to a point above said hollow casing, gearing connect- 30 ing said vertical drive shaft with said power gear, a steering column, gears connecting said steering column to said hollow casing, and a power gear guard element covering at least a portion of said gear, said guard element having a portion ex- 35 tending therefrom, and said extending portion constituting a journalled supporting brace for said steering column.

BOGOIA STREZOFF.
